UNITED STATES PATENT OFFICE

94,277

DESIGN FOR A REEL

Edward J. McMahon, Bronson, Mich., assignor to Bronson Reel Company, Bronson, Mich., a corporation of Michigan

Application April 30, 1934, Serial No. 51,587

Term of patent 14 years

To all whom it may concern:

Be it known that I, Edward J. McMahon, a citizen of the United States, residing at Bronson, Branch County, Michigan, have invented a new, original, and ornamental Design for a Reel, of which the following is a specification.

The design is shown in the accompanying drawing, which forms a part hereof, and in which:

end elevation of a reel embodying the invention;

I claim:

The ornamental design for a reel, substantially

EDWARD J. McMAHON.
